Primary Examiner — Messina L Smith*Assistant Examiner* — Noah Perez(74) *Attorney, Agent, or Firm* — RatnerPrestia(57) **CLAIM**

The ornamental design for an attachment for tablet computer, as shown and described.

DESCRIPTION

FIG. 1 is a front perspective view of an attachment for tablet computer showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in FIGS. 1-8 depict portions of the attachment for tablet computer that form no part of the claimed design. The dot-dash broken lines represent the boundaries of the claim and form no part of the claimed design.

1 Claim, 6 Drawing Sheets(56)
